UNITED STATES PATENT OFFICE.

CLINTON B. REPP, OF NEW YORK, N. Y.

PHONOGRAPH.

1,213,413.

Specification of Letters Patent. Patented Jan. 23, 1917.

Application filed January 19, 1912. Serial No. 672,067.

To all whom it may concern:

Be it known that I, CLINTON B. REPP, a citizen of the United States, residing at the borough of Manhattan, in the city, county, and State of New York, have invented certain new and useful Improvements in Phonographs, of which the following is a specification, reference being had therein to the accompanying drawings, which form a part thereof.

10 My invention relates to phonographs, and more particularly to a type of phonograph patented to me in and by Letters Patent of the United States No. 1,003,655, of September 19, 1911, wherein the sound vibrations are transmitted to a stationary diaphragm through a non-oscillatory transmitter arm.

15 The main object of my invention is to provide a phonograph of this character adapted to be adjusted for use with either a gramophone or a graphophone record.

20 A further object is to provide a phonograph wherein the transmitter arm is supported by a supplemental arm, and independent means are provided for developing pressure upon the diaphragm through the transmitter arm, and for bringing the stylus point into the desired relation to, and intimate contact with, the record.

25 A still further object is to provide a phonograph wherein the desired pressure upon the diaphragm will be developed in a manner which will permit this pressure to be applied either substantially axially of the diaphragm, or at an angle to its axis, in order to facilitate the adjustment of the instrument to use with either gramophone or graphophone records.

30 A still further object is to provide a phonograph wherein the sound vibrations are transmitted to a stationary diaphragm through a non-oscillatory transmitter member, and wherein said transmitter member will be held substantially stationary, the record having movement relative thereto to bring every portion of the record within, and into the operative relation to, the stylus carried by the transmitter arm.

35 A still further object is to provide a phonograph employing a substantially fixed stylus point and a traveling record support adapted to have movement relative to the stylus, wherein sufficient play will be afforded in the stylus support to compensate for any irregularities in the record or any lack

of uniformity in the feed of the traveling record support.

40 A still further object is to provide in a machine of the character immediately above referred to, means whereby as the stylus is raised from the record such movement will simultaneously render the record feeding mechanism inoperative so as to permit the return of said record to the starting position.

45 A still further object is to provide a clutch device controlling mechanism for the record feeding mechanism which will be operative at any point in the movement of the said mechanism, and which when the stylus point 70 is placed upon the record, will automatically render the clutch device of the record feeding mechanism operative. And a still further object is to provide a structure of this kind, which will be simple in design, reliable 75 in its operation, and inexpensive to produce.

50 The invention consists primarily in a phonograph, embodying therein a rotary record support, a fixed amplifier, a substantially stationary transmitter arm connected with 80 said diaphragm and carrying a stylus point, and means for causing said record support to have lineal traverse relatively to said stylus; and in such other novel features of construction and combination of parts as 85 are hereinafter set forth and described, and more particularly pointed out in the claims hereto appended.

55 Referring to the drawings:—Figure 1 is a vertical section of a phonograph embodying my invention; Fig. 2 is a vertical section transversely of the line of movement of the motor frame; Fig. 3 is a plan view thereof; Fig. 4 is a detail view in perspective of the transmitter mechanism and the sound box; 90 Fig. 5 is a horizontal section showing the motor and the parts appurtenant thereto; Fig. 6 is a detail view of the connection between the rigid supporting arm and the transmitter arm; and Fig. 7 is a detail view 95 of the structure for applying a tensional stress to the diaphragm.

60 Like letters refer to like parts throughout the several views.

65 In the embodiment of my invention shown in the drawings, *a* indicates a frame carried by a cabinet having a top slab *a'* thereon. Carried by the said frame is a plurality of guide rods *b* upon which are mounted the plates *c* of a spring motor of

any desired construction, which is shown merely conventionally in the accompanying drawings.

Included in the motor is a spring drum c' carrying the first gear c^2 of a train of gears, the last gear c^3 of which train is splined upon a feed screw c^4 journaled in the frame a . By this means the entire motor is permitted to travel within the cabinet while at the same time rotating the feed screw c^4 irrespective of the position of the motor relative thereto. Also driven from the same gear train is a beveled gear d , enmeshed with a beveled gear upon the vertical shaft e having mounted thereon, so as to be rotatable therewith, the record supporting table e' , which in the form of the invention shown occupies a horizontal position. To secure the desired stability of the said table, I provide brackets e^2 having bearings in which the shaft e is mounted adjacent to the opposite ends thereof. The cabinet top has a slot a^2 therein, through which the shaft e projects, said slot being of a length sufficient to admit of a feeding movement approximating the radius of the table e' .

Mounted in the cabinet adjacent to the feed screw c^4 , is a rock shaft f having splined thereto an arm, mounted upon and movable with the motor frame, said arm carrying a nut f^2 adapted to engage the said feed screw. Keyed to said shaft is a weighted arm f^4 adapted to normally force said nut f^2 into engagement with said feed screw c^4 , thus positioning these parts so that with the rotation of said feed screw c^4 the entire motor and the record table will travel radially of the latter. This construction is employed in order to permit the nut to be thrown into and out of gear with the feed screw at any point of the travel of said table in order to permit the adjustment of the record, or the stoppage of the machine, in a manner which will be hereinafter referred to.

Mounted upon the top slab a' at a point thereof without the range of movement of the table e' , is a sound box, g , the supporting means for which comprises a plurality of standards g' . This construction results in a sound box occupying a fixed position. Within the sound box g is a diaphragm g^2 , the detailed construction of these parts being that now commonly employed, or any other desired construction that may be satisfactorily employed.

Secured to the top slab a' axially below the diaphragm g^2 , is a post h having on the top thereof a yoke h' , the axis of which yoke extends vertically and coincides with that of the diaphragm. Mounted in the yoke h' by means of a horizontal pivot i' , is a supporting arm i preferably of metal, the pivot i' connecting said arm with said yoke projecting beyond said yoke so as to constitute

a stud to be utilized in effecting the adjustments of the instrument for use with graphophone records. The arm i projects substantially radially of the diaphragm g^2 toward and over the record table e' , and the outer end thereof carries a universal joint i^2 carrying a split collar i^3 adapted to receive and engage the outer end of the transmitter arm. Projecting downwardly from the said arm i , adjacent to the post h , is a post j , and extending from said post j and secured to the post h is a coiled spring k , adapted to exert a downward pressure upon said arm for the purpose of developing the desired pressure of the stylus point upon the record carried by the table e' . Also carried by the arm i is an upwardly projecting extension l directly beneath and terminating adjacent to the diaphragm, said extension being adapted for use in adjusting the instrument for use in connection with gramophone records.

The means for conveying the sound vibrations indicated upon the record to the diaphragm, comprise a transmitter arm m preferably of wood, which is firmly secured in position within the split collar i^3 adjacent to that end thereof carrying a mount m' adapted to receive the stylus point n . This stylus point is secured within said mount by means of the set screw m^2 . The other end of said transmitter arm is connected to the diaphragm g^2 by means of a flexible loop g^3 carried by said diaphragm and attached to said transmitter arm in the manner described in my patent above referred to. Secured to the end of said transmitter arm adjacent to the diaphragm is a small coiled spring o the free end of which is provided with a loop adapted to pass over the protruding end of the pivot i' or of the extension l , according to whether it is desired to use the instrument in connection with graphophone or gramophone records.

While the action of the spring k will tend to develop the desired pressure upon the diaphragm to place the loop connection in tension, to provide independent means for increasing this pressure, I mount upon the split collar i^3 a spring extension p between which and the hook i^4 upon the arm i is a coiled spring q adapted to exert a torque upon the universal joint i^2 to place the diaphragm under sufficient tension, the spring o supplementing the action of the spring q and controlling the direction of the application of pressure.

The arm i is capable of a very limited movement in the yoke h' , this movement being merely that necessary to permit sufficient play of the outer end of said arm and of the stylus point n to compensate for irregularities in the indicated sound waves upon the record and inequality in the feeding movement of the record, caused by lost

motion in the feed screw c^4 . A movement equal to the width of eight or ten sound wave grooves is sufficient to eliminate all imperfections in the reproduction due to such irregularities, thus requiring but very little play at the point of support of the said arm i .

In order to place the feeding or traveling of the motor under the control of the transmitter arm m , and its supporting arm i , I secure to the arm f^4 a connection rod r carrying an angular plate s having a forked end s' adapted to straddle the said arm i in a manner to cause the raising or lowering 15 of said arm to oscillate the shaft f to throw the nut f^2 out of engagement with the feed screw c^4 or permit it to drop into such engagement. Thus, it will be observed, as the stylus is raised from the record, the feeding 20 movement of the record table e' will instantly cease, and the motor driving said table will be freed so as to permit said table to be restored to its normal position where the edge thereof will be directly beneath the 25 stylus point, or permit the adjustment of said plate to bring the stylus point into engagement with the grooves containing the indicated sound vibrations upon the record.

The operation of the herein described 30 phonograph is substantially as follows:— Inasmuch as the details of the motor are old and well known in this art, the showing of this motor and the description thereof is merely conventional, it being assumed that 35 the motor is so constructed as to cause a rotation of the various parts at a predetermined rate of speed.

When it is desired to start the motor, the transmitter arm m is raised, carrying with it 40 the supporting metallic arm i , which raises the rod r and the arm f^4 , thus oscillating the shaft f . This movement of the shaft disconnects the nut f^2 from the feed screw c^4 , permitting the entire motor to be moved 45 relative to the said transmitter arm by means of the record table e' . When the record upon the table e' is in a position where the stylus n will properly engage the groove upon the upper surface thereof, the said 50 transmitter arm is lowered, reversing the movement of the nut f^2 and throwing it into engagement with the feed screw c^4 so that when the motor is started, the rotation of said screw will cause said nut to travel 55 along it. This movement of the said nut will impart a lineal traverse to the motor and to the table e' in a manner to bring every portion of one radius of said record within the operative range of the said transmitter arm and stylus. The pitch of the 60 feed screw c^4 will be such as to correspond with that of the spiral groove upon the record, the slight play of the transmitter arm m described above compensating for any differences in pitch between that of the screw 65

and that of the groove of the record. As the motor is thus caused to travel beneath the top slab a' , the shaft e will be simultaneously rotated to impart the desired rotary movement to the record so that while the 70 stylus remains substantially stationary, the record has movement relative thereto. As the stylus is brought into engagement with the record, the springs developing the desired pressure between the stylus and the record, supplemented by the weight upon the arm f^4 , will bring the nut into mesh with the screw and will preserve the proper relation between these parts. As the record thus travels lineally toward, and rotates beneath, the stylus n , the horizontal pivots i' of the arm i will permit said arm and the transmitter arm m to rise and fall with the irregularities in the movement of the table e' , the arm m moving about an axis coinciding with its point of connection with the flexible loop g^3 connecting it with the diaphragm g^2 . There is no pivotal movement of the collar i^3 , the arm m with the exception of the slight lateral play above referred 80 to, having movement only upon the said loop g^3 . As the record moves in relation to the stylus, the sound waves indicated thereon will develop in the transmitter arm vibrations corresponding in frequency with 85 those indicated upon the record, which vibrations will pass to the diaphragm and produce sound waves in the manner described in my patent hereinbefore referred to. The said diaphragm is always in tension from the springs k and q , the action of these springs tending to exert a pull upon the diaphragm in a direction slightly obliquely of the axis thereof so that when no supplemental means are used, the instrument will reproduce sound from either a 90 graphophone or a gramophone record. To increase the amplitude of the reproduction, however, I provide the adjustment spring o which increases the tension upon the diaphragm and gives a more definite direction to the stress occurring thereon. When, for example, the spring o is drawn down and secured to the protruding end of the pivot i' , a substantially vertical pressure results, 100 while if this spring be drawn at an angle to the axis of the diaphragm, and secured to the upwardly projecting extension l , the lateral pressures will be increased to adapt it for use with a gramophone record.

The universal bearing for the collar i^3 is solely for the purpose of permitting the movement of the transmitter arm m for accomplishing the adjustment above referred 110 to.

The arms of the forked end s' of the plate s straddle the arm i and are spaced apart sufficiently so that when the nut f^2 is in engagement with the feed screws c^4 neither of said arms will be in engagement with the 120

arm in an arrangement which I use so as to prevent the development of any vibrations in said plate through its contact with said arm, or the transmission of vibrations from 5 the feeding mechanism to the sound reproducing mechanism.

It is not my intention to broadly claim in this application the metallic arm supporting the outer end of the transmitter arm, nor 10 the universal joint connecting these two arms; nor is it my intention to claim broadly a machine employing a transmitter arm of the character described provided with means for varying the direction of the application 15 of pressure upon the diaphragm, such being subject matter of other applications of mine, pending concurrently herewith.

I believe it to be broadly new however, to incorporate in a machine of this character 20 a support for a record, a stationary transmitter arm having no pivotal movement about bearings intermediate its ends, and means for imparting simultaneously lineal and rotary movement to said record support, and I intend to claim such broadly.

Having described my invention, what I claim as new and desire to have protected by Letters Patent, is:—

1. A phonograph embodying therein a 30 fixed amplifier, a transmitter arm, one end of which is adapted to carry a stylus point, means connecting the other end thereof with, and adapted to transmit vibrations from said arm to, said amplifier, a rigid supporting arm for said transmitter arm, one end of which is connected to said transmitter arm adjacent that end thereof adapted to carry the stylus point, means supporting the other end of said arm and holding it against 40 lateral movement while permitting vertical movement, a record support, and means causing said record support to have lineal traverse relatively to a stylus carried by said arm, and to have simultaneous rotary movement.

2. A phonograph embodying therein a 50 fixed amplifier, a transmitter arm, one end of which is adapted to carry a stylus point, means connecting the other end thereof with, and adapted to transmit vibrations from said arm to, said amplifier, a rigid supporting arm for said transmitter arm, one end of which is connected to said transmitter arm adjacent that end thereof adapted to 55 carry the stylus point, means supporting the other end of said arm and holding it against lateral movement while permitting vertical movement; a record support, means causing said record support to have lineal traverse relatively to a stylus carried by said arm, and to have simultaneous rotary movement, and means adapted to place said amplifier under tension through the connecting means between said transmitter arm and 65 said amplifier.

3. A phonograph, embodying therein a rotary record support, a fixed amplifier, a substantially stationary transmitter arm, carrying a stylus point and adapted to be connected with and transmit vibrations to, 70 said amplifier, means for causing said record support to have lineal traverse relatively to said stylus and to have simultaneous rotary movement, means adapted to place said amplifier under tension through 75 the connection between said transmitter arm and said amplifier, and means whereby the direction of this pressure may be varied to adapt the machine for use in connection with either graphophone or gramophone records. 80

4. A phonograph, embodying therein a rotary record support, a fixed amplifier, a rigid supporting arm mounted upon horizontal pivots below said amplifier, said arm having slight lateral play, means exerting a 85 downward pressure upon said arm, a substantially stationary transmitter arm attached adjacent to one end thereof to said supporting arm and having the other end thereof connected with, and adapted to 90 transmit vibrations to, said amplifier, said transmitter arm being adapted to carry a stylus point, and means for causing said record support to have lineal traverse relatively to said stylus and to have simultaneous 95 rotary movement.

5. A phonograph, embodying therein a rotary record support, a fixed amplifier, a rigid supporting arm mounted upon horizontal pivots below said amplifier, said arm 100 having slight lateral play, means exerting a downward pressure upon said arm, a substantially stationary transmitter arm attached adjacent to one end thereof to said supporting arm and having the other end 105 thereof connected with, and adapted to transmit vibrations to, said amplifier, said transmitter arm being adapted to carry a stylus point, means for causing said record support to have lineal traverse relatively to said stylus and to have simultaneous 110 rotary movement, and means adapted to place said amplifier under tension through the connection between said transmitter arm and said amplifier.

6. A phonograph, embodying therein a rotary record support, a fixed amplifier, a rigid supporting arm mounted upon horizontal pivots below said amplifier, said arm having slight lateral play, means exerting a 115 downward pressure upon said arm, a substantially stationary transmitter arm attached adjacent to one end thereof by a universal joint to said supporting arm and having the other end thereof connected with, and adapted to transmit vibrations to, said amplifier, said transmitter arm being adapted to carry a stylus point, means for causing said record support to have lineal traverse relatively to said stylus and 120

125

130

to have simultaneous rotary movement, and relatively movable coöperating means whereby a tensional stress may be applied to said amplifier and said transmitter arm 5 may be shifted about said universal joint to vary the direction of the application of the stress tensioning said amplifier whereby the phonograph may be adjusted for use with either graphophone or gramophone records.

10 7. A phonograph embodying therein a fixed amplifier, a transmitter arm, one end of which is adapted to carry a stylus point, means connecting the other end of said arm with, and transmitting vibrations therefrom to, said amplifier, a feed screw, a frame adapted to receive lineal traverse from said feed screw, a rotary record support carried by said frame, a spring motor carried by said frame, means actuated by said motor 15 for imparting a rotary movement to said record support simultaneously with the lineal traverse of said frame, and means preventing movement of said transmitter arm across the record by and in accordance with 20 the indicated sound waves upon a record carried by said support.

8. A phonograph embodying therein a fixed amplifier, a transmitter arm, one end of which is adapted to carry a stylus point, 30 means connecting the other end of said arm with, and transmitting vibrations therefrom to, said amplifier, a feed screw, a frame adapted to receive lineal traverse from said feed screw, a rotary record support carried by said frame, a spring motor carried by said frame, means actuated by said motor 35 for imparting a rotary movement to said record support simultaneously with the lineal traverse of said frame, means preventing movement of said transmitter arm across the record by and in accordance with the indicated sound waves upon a record carried by said support, and means whereby said motor frame may be connected with and disconnected 40 from said feed screw at will.

45 9. A phonograph, embodying therein a rotary record support, a fixed amplifier, a rigid supporting arm, mounted upon horizontal pivots below said amplifier, said arm having slight lateral play, means exerting a downward pressure upon said arm, a substantially stationary transmitter arm attached adjacent to one end thereof to said supporting arm and having the other end 50 thereof connected with, and adapted to transmit vibrations to, said amplifier, said transmitter arm being adapted to carry a stylus point, a feed screw, a spring motor adapted to receive lineal traverse from said 55 feed screw, a gear driven by said motor slidably mounted upon said feed screw, a nut carried by said motor, means actuated by said supporting arm whereby said nut may be thrown into or out of engagement with 60 said screw, and means carried by said motor 65

for imparting a rotary movement to said record support simultaneously with the lineal traverse of the motor.

10. A phonograph, embodying therein a rotary record support, a fixed amplifier, a rigid supporting arm, mounted upon horizontal pivots below said amplifier, said arm having slight lateral play, means exerting a downward pressure upon said arm, a substantially stationary transmitter arm attached 70 adjacent to one end thereof to said supporting arm and having the other end thereof connected with, and adapted to transmit vibrations to, said amplifier, said transmitter arm being adapted to carry a stylus point, a feed screw, a spring motor adapted to receive lineal traverse from said feed screw, a gear driven by said motor slidably mounted upon said feed screw, a nut carried by said motor, and slidably mounted upon a rocking 75 shaft, an arm carried by said shaft, a rod secured to said arm and adapted to straddle said supporting arm, whereby said nut may be thrown into or out of engagement with said screw as said supporting arm is lowered 80 or raised to engage the stylus with, or disengage it from, the record, and means carried by said motor for imparting a rotary movement to said record support simultaneously with the lineal traverse of the motor. 85

11. A phonograph embodying therein a record support, means actuating said support, a fixed sound box, a diaphragm mounted therein, a transmitter arm adapted to carry a stylus point at one end thereof, a flexible connection between the other end of 90 said arm and said diaphragm, a rigid supporting arm adapted to have said transmitter arm mounted thereon adjacent to the stylus, a universal joint connecting said transmitter arm and said supporting arm, means acting through said supporting arm whereby said transmitter arm is normally forced toward a record, projections substantially axially below said diaphragm and below and 95 eccentrically thereof, and an elastic member, one end of which acts upon said connection between the transmitter arm and the diaphragm, and the other end of which is adapted to be connected to either of said 100 projections to adjust the machine for use with a graphophone or a gramophone record.

12. A phonograph, embodying therein a record support, means actuating said support, a fixed sound box, a diaphragm mounted therein, a transmitter arm adapted to carry a stylus point at one end thereof, a flexible connection between the other end of 120 said arm and said diaphragm, a rigid supporting arm adapted to have said transmitter arm mounted thereon adjacent to the stylus, a pivotal connection between said transmitter arm and said supporting arm, means acting through said supporting arm 125

means actuated by said supporting arm 130

whereby said transmitter arm is normally forced toward a record, a spring member carried by said pivotal connection, and an elastic member extending from said spring member downwardly to said supporting arm, whereby a rotative movement is exerted upon said pivotal connection to develop pressure upon said diaphragm.

In witness whereof, I have hereunto affixed my signature in the presence of two subscribing witnesses, this 8th day of January, 1912.

CLINTON B. REPP.
